TOILET PAPER HOLDER

Sigmund J. Gralewicz, Milwaukee, Wis.

Application March 26, 1956, Serial No. 40,760

Term of patent 7 years

(Cl. D4—3)

Fig. 1

I claim:

The ornamental design for a toilet paper holder, as shown.
